UNITED STATES PATENT OFFICE

100,582

DESIGN FOR A GAME BOARD

Frederick Scheff, New York, N. Y.

Application April 17, 1936, Serial No. 62,178

Term of patent 7 years

To all whom it may concern:

Be it known that I, Frederick Scheff, a citizen of the United States, residing at 68 Nassau Street, New York city, county of Manhattan, State of New York, have invented a new, original, and ornamental Design for a Game Board, of which the following is a specification, reference being had to the accompanying drawing, forming part thereof.

The figure is a plan view of a game board, showing my new design.

The game board is of no appreciable thickness.

I claim:

The ornamental design for a game board as shown and described.

FREDERICK SCHEFF.
